HAIR CURLER

William Huppert, New York, N. Y., assignor to
Delamere Company, Inc., a corporation of Del-
aware

Application May 23, 1936, Serial No. 81,371

4 Claims. (Cl. 132—41)

This invention relates to a hair curler of the type comprising a form around which the hair may be wound and a wire loop for clasping the hair wound thereon, the bight of the loop, in its closed or clamping position, engaging the end of the form. Curlers of this type are generally provided with a pivotally connected finger which is adapted to be pressed down against the form, either with or without spring pressure, to clamp the hair ends on the form prior to winding.

An example of this type of curler is illustrated and described in Patent No. 1,739,301 of December 10, 1929 to Abraham Goodman and Jacob Goodman. Heretofore the loop element of such curlers has been formed with two inturned ends, which ends extend inwardly through holes in the curler. In order to prevent the loop from becoming disengaged, the ends, after insertion in the curler, are upset or bent upwards.

This bending necessitates a further operation and is objectionable because it tends to vary the radial length of the arms of the loop with the result that in some cases the loop is too short properly to engage the end of the curler, and, in other cases, it is too long. In either case the defect must be remedied before the curler becomes a commercially salable article. These curlers are manufactured in very large quantities to be sold at a low price and hence all additional operations tend to increase the cost of manufacture of the article.

My invention aims to overcome these objections by the provision of a wire loop which is so constructed that it may be easily assembled with the curler and that when so assembled it has a substantially definite fixed radial length of such dimension that the bight of the loop, in its closed position, will properly engage the end of the curler.

Other objects and advantages of the invention will appear from the following description thereof, reference being had to the accompanying drawing, in which:

Figure 1 is a plan view of the wire loop element of the curler;

Fig. 2 is a side view of one form of the curler;

Fig. 3 is a view of the same, partly in section, taken on the line 3—3 of Fig. 2;

Fig. 4 is a vertical sectional view taken on the line 4—4 of Fig. 2; and

Fig. 5 is a similar vertical sectional view showing a modification.

The wire loop element indicated generally by the reference character 10 is made of a single length of wire bent to form two side portions or

arms 11, which arms may be slightly bowed outwardly as shown, and a connecting end portion or bight 12. Each of the two ends of the wire extend inwardly in a relatively short portion 13 and terminates in a quadrantal or arcuate shaped portion 14 of small radius. The radius of curvature of the portion 14 is such that a tangent to the curve will form an acute angle with the arm 11, as indicated by the angle X in Figure 1. The extremities of the two curved portions are directed toward each other. The portions 13 function as fulcrums on which the loop turns or swings while the curved portions 14 provide means for preventing accidental disengagement of the ends when they are inserted in the curler. It is an essential feature of my invention that the inturned ends of the loop be preformed or prebent in substantially the form just described, that is to say, the ends of the loop are bent to shape before they are inserted into the curler and not afterwards. The loop may be conveniently formed in the desired shape in a die. This assures uniformity in bending the wire into proper predetermined shape. Preferably, all of the parts of the loop lie in a single horizontal plane.

The curler in the particular form shown in the drawing comprises a slightly conical tubular member 15 and a semi-tubular clamp arm 16 adapted to lie on or press against the member 15. The arm 16 has ears 17, which ears have holes 18 that align with corresponding holes 19 in the tube 15 for reception of the inturned ends of the loop element 10.

The radial length of the loop member, indicated as R in Fig. 1, that is, the length from the inturned portion or fulcrum 13 to the cross piece or bight 12 of the loop, may be substantially equal to the length from the hole 18 to the front end 20 of the tube 15 so that when the loop is swung down to its closed or hair clasping position, as shown in Figs. 2 and 3, the bight of the loop will engage the end of the curler with sufficient tension to hold it in place against accidental dislodgment but not sufficiently tight to prevent it from being easily unfastened when it is desired to take the curler out of the hair. If desired, the end 20 of the tube 15 may be provided with shallow notches 21 in which the bight of the loop engages in closed position. The bowed form of the arms of the loop give the loop sufficient resiliency so that it may readily be swung into or out of engagement with the end of the form.

In the form of curler illustrated in Figs. 2 to 4, inclusive, the prebent inturned ends of the loop serve to connect the elements 15 and 16 pivotally

together. In the modification illustrated in Fig. 5, the ears 17 of the clamp arm 16 are provided with inwardly extending bosses 22 which engage in similar bosses 23 in the member 15 to pivotally connect the parts together independently of the wire loop element. Any means for pivotally connecting said members may be employed.

The length of each of the portions 13 of the in-turned ends of the loop is substantially equal to or 10 slightly greater than the combined thickness of the two members 15 and 16 at their point of pivotal connection.

In assembling the curler, the prebent ends of the loop are inserted through the aligned holes 18 15 and 19. In doing this, one end is inserted first and then the other. The radius of the curvature of the curved portions 14 of the end of the loop is such that they may be easily inserted through the holes in the tubular and semi-tubular members 20 and held in place within the tubular member against accidental disengagement; and that the loop may be swung freely about its axis without having its inturned ends bind against the bore of the tubular member.

25 While for the purpose of illustration I have shown the loop element applied to one form of curler, it is to be understood that I do not limit my invention in this respect as it may be applied to other known forms, and that various modifications in the details of the loop element may be made within the scope of the invention.

What I claim is:—

1. A hair curler comprising a tubular body and a wire clasp swingably secured to the body, said

clasp having spaced apart side portions interconnected at one end and terminating at their opposite ends in preformed curved portions that are directed toward each other and extend into the tubular body to prevent accidental detachment of the clasp and to permit of swinging it relatively to the body through an arc having a radius of predetermined length.

2. A hair curler comprising a tubular body and a wire clasp swingably secured to the body, said clasp having spaced apart side portions interconnected at one end and terminating at their opposite ends in preformed portions of reverse curvature that are directed toward each other and extend into the tubular body to prevent accidental detachment of the clasp and to permit of swinging it relatively to the body through an arc having a radius of predetermined length.

3. A hair curler comprising a tubular body, a clamping member hinged to the body, and a wire clasp swingably secured to the body, said clasp having preformed inturned curved ends that extend into the body to secure the clasp swingably to the body against accidental detachment.

4. A hair curler comprising a tubular body, a clamping member hinged to the body, and a wire clasp swingably secured to the body, said clasp having preformed curved ends that are directed toward each other and extend into the body at the point of hinging of the clamping member to secure the clasp swingably to the body against accidental detachment.

WILLIAM HUPPERT.
